UNITED STATES PATENT OFFICE.

HENRY PATERSON GRAY, OF PATERSON, NEW JERSEY.

BUNG-FAUCET AND CONNECTION.

SPECIFICATION forming part of Letters Patent No. 373,826, dated November 29, 1887.

Application filed January 27, 1887. Serial No. 225,691. (No model.)

To all whom it may concern:

Be it known that I, HENRY PATERSON GRAY, of Paterson, Passaic county, New Jersey, have invented a new and Improved Combination 5 Bung - Bushing, Faucet-Stopper, and Connection, for the purpose of drawing and filling liquids which are contained in tanks, barrels, cans, vats, casks, &c., adapted to the use of dealers in liquors, bottlers, brewers, and others, of which the following is a specification.

The features of my invention I will describe more particularly with reference to the accompanying drawings.

Figure 1 is a metal bushing having an external 15 flange, an internal flange, a small recess, and holes, also threaded suitably externally and internally for the purposes required. Fig. 2 is a vertical transverse section through the entire invention. Fig. 3 is a combined threaded 20 bung adapted to fit bushing represented in Fig. 1. Said bung contains a valve provided with a perforated disk, a screw, and holes or apertures, for the purposes required. Fig. 4 is an end view showing the inner end of the 25 invention. Fig. 5 is an end view showing the outer end of my invention. Figs. 6, 7, and 8 are detail views of the valve contained in Fig. 3. Fig. 9 represents a key to open and close the valve. Fig. 10 represents a key - wrench 30 used to adjust the parts represented by Figs. 1, 3, and 4.

Similar letters of reference indicate corresponding parts.

A is a metal bushing, provided with external 35 flange, G, and holes H to receive key-wrench, by which it is screwed in place; also the external thread, R, and internal thread, t, the internal flange, i, shoulder i², and recess for holding packing-ring i³, made substantially for 40 the purposes required.

B is a combined bung-faucet and connection, provided with external thread, t', the internally-threaded aperture K, the key-hole c, and the wrench-holes H', adapted to fit the wrench 45 at n; also the hollow conical-shaped valve D and screw x, the perforated strainer z, aperture c' of said valve, and the shoulders y of said valve, for the purpose of forming a stop when the valve is opened or closed and for holding 50 the same in place, all made substantially for the purposes required and herein mentioned.

E is a flanged nut having holes P to fit key-wrench at m, and thread o, adapted to fit the bushing A.

D is a hollow conical valve having the hole 55 w for an outlet, the shoulders y, and the perforated disk or strainer z, and aperture c'. Said aperture is to receive the key by which said valve is opened and closed, and it is round or circular at its center, and has extending from its periphery two slots, c². The circular part 60 of the aperture is the same in diameter as the diameter of the key-hole c. The key c² passes through hole c into aperture c'. The handle of said key is pressed in the hand, and the lugs 65 c⁴ are thus thrown out and into slots c². Thus I am able to unlock or operate the valve D. c³ is a spring-key for operating the valve D, and is fitted to the aperture c'.

F is a substantial metal key-wrench, provided 70 with pins m and n, and adapted to fit the holes H, H', and P, the whole made substantially for the purposes of operating the bushing A, the nut E, and bung B. The pins n are made longer than pins m. The object of 75 this is to prevent interference with flange G while bung B is being screwed to place.

There is loss and danger sustained in tapping barrels of beer of different kinds caused by pressure. By use of my invention the loss 80 and danger are avoided. The use of the bung and bung-hole in side of the barrel is obviated. Barrels can be filled without waste through a bung-hole in end, and can be cleansed and refilled through the same aperture. The liquids 85 are strained while passing through the valve. The strainer can be removed, if necessary, or replaced by another one. A good place is obtained to adjust a revenue-stamp where it must be punctured or destroyed before the 90 valve can be turned to make an outlet. The stock cut out to admit my invention is replaced by screwing the same in place, thereby retaining the former strength of barrel or vessel in which it is placed. When the key is removed, the valve is locked. Thus it can be 95 locked with valve open or shut.

The invention, when properly attached, is adapted to have no projecting ends, but is flush inside and out.

Having thus described my invention, I claim 100 as new and desire to secure by Letters Patent—

1. In a combined bung-bushing and faucet, substantially as shown and described, the conical hollow valve D, having the shoulders y, side opening, w, circular opening e' in its closed end, and lateral slots e², extending outwardly from said opening, said openings adapted to register with openings e and K in the faucet B, substantially as shown and described.
2. In a combined bung-bushing and faucet, substantially as shown and described, the combination of the faucet B, adapted to fit in the bung-bushing A and having the internal threaded opening K, circular key-hole e, holes H in its inner end, and conical seat adapted to receive valve D, with conical valve D, working in said seat, having side opening w, situated to register with opening K, shoulders or stops y, adapted to be arrested by the screw x, circu-

lar opening or key-hole e' in its closed end, and lateral slots e², extending outward from said key-hole, adapted to be operated by a suitable key, substantially as shown and described.

3. In a combined bung bushing and faucet, substantially as shown and described, the combination of key-wrench F, provided with pins m and n, with the bushing A, flanged nut E, and faucet B, said pins being adapted to fit in perforations H, H', and P of said parts, substantially as shown and described, and for the purposes set forth.

HENRY PATERSON GRAY.
